UNITED STATES PATENT OFFICE

CHARLES LESLIE NEWLAND, OF ELTHAM, ENGLAND.

CLOSURE FOR BOTTLES, JARS, AND OTHER RECEPTACLES.

1,426,209.

Specification of Letters Patent. Patented Aug. 15, 1922.

Application filed May 2, 1922. Serial No. 557,888.

To all whom it may concern:

Be it known that I, CHARLES LESLIE NEWLAND, a subject of His Majesty the King of England, and resident of Eltham, in the county of Kent, Kingdom of England, have invented certain new and useful Improvements in Closures for Bottles, Jars, and Other Receptacles, of which the following is a specification.

10 This invention refers to improvements in closures for bottles, jars and other receptacles of the kind comprising a resilient disc having a central bulged portion capable of being sprung into opposite positions on each 15 side of a horizontal plane, and having a plurality of marginal fingers integral with said central portion and adapted to be moved away from or into contact with the beaded edge of the receptacle according to whether 20 the flexible disc is sprung in towards the said fingers or away from same.

Heretofore in such closures it has been proposed in order to prevent the bulging disc from being depressed and the cap or closure 25 accidentally opened, to provide the said disc with a circumferential marginal portion or upstanding flange, but it has been found in practice that if this marginal portion or upstanding flange is made of sufficient size to 30 position the central bulge entirely below the level of its upper edge, it has a detrimental effect upon the grip of the fingers on the receptacle and also upon the springing of the central disc.

35 Now according to the present invention in order to overcome the said disadvantage I provide the body of the disc or cap with a plurality of upstanding projections near its periphery which may be stamped up from 40 the metal thereof or otherwise provided thereon. The said projections may be of any convenient shape or configuration and they are so arranged or disposed as not to interfere with the free movement of the fingers when the central disc is sprung.

45 In order that the present invention may be clearly understood and readily carried into effect it is hereinafter described with reference to the accompanying drawings, in 50 which:—

Figure 1 is an outside elevation of a cap constructed in accordance with this invention and applied to a bottle or jar;

Figure 2 is a plan view of said cap;

55 Figure 3 is a transverse vertical section of the said cap showing the same in its closed

position as when applied to the beaded rim of the bottle or jar;

Figure 4 is a similar view showing the cap sprung inwardly as when in its released 60 position;

Figures 5 and 6 are plan views of caps of slightly modified construction;

Figure 7 is a side elevation of the cap shown in Figure 6, and 65

Figure 8 is a sectional elevation of a portion of the cap showing one of the projections pulled up on its under or concave side.

In carrying the present invention into effect I may, as shown in Figures 1 to 4, provide such a disc *a* with a single semispherical upstanding projection *b* in the central disc near the middle of each depending finger *c* and preferably spaced equi-distant from each of the slots *d* dividing the fingers 75 *c* from each other.

In a further slightly modified construction, instead of providing each finger with a single projection I may, as shown in Figure 5, provide two projections *b* for each 80 finger *c* and space them in relation thereto so that they come adjacent to the said slits *d*, thus leaving a central portion of the disc in the middle of the finger plain or free.

In a further slightly modified construction, instead of providing semispherical or like projections *b* these projections may be flattened, as shown in Figures 6, 7 and 8, so as to coincide with the periphery of the disc *a* to give a more or less sinuous appearance to the edge thereof, as shown in Figure 7, providing in effect a discontinuous flange, the raised or crest portions of the said projections *b* coming in the centre of each finger *c* and merging away into the flat 95 edge portion of the disc just before or adjacent to the slits *d* dividing the fingers.

In certain cases it may be desirable or necessary, as shown in Figure 8, in order to provide a flat or level marginal surface on 100 the underside of the flexible disc *a*, to fill in with metal or other suitable material *e* the recesses formed therein by the projections *b* being stamped up from the metal thereof.

A further advantage arising from the use 105 of my invention is that the projections *b* will not only serve to prevent accidental opening when packed but should any receptacle already be open the pressure of packing will cause the closure to be sealed. This function 110 is due to the fact that the projections are always above the level of the disc *a* even

when it is bulged outwardly, as shown in Figure 3, and also by reason of the fact that the centre of the projection is always outside the high point or fulcrum line of the beaded edge *f* of the receptacle, an arrangement which ensures that pressure on the projections *b* will cause the disc *a* to be swung outwards into the position shown in Figure 3. This is of great advantage as the closures 10 can be loosely placed in position on the receptacles and can be closed thereon in a suitable press by hand or other power.

It will thus be seen that by the present arrangement I am enabled to provide projections of sufficient height to leave the central bulge on the flexible disc completely below their level and at the same time not to destroy the rigidity of the depending fingers and the central disc, or to reduce the grip 20 effect of the fingers on the edge of the receptacle.

What I claim is:—

1. A closure for bottles, jars and other receptacles, comprising a resilient disc having a central bulged portion capable of be- 25

ing sprung into opposite positions on each side of a horizontal plane, a plurality of marginal fingers integral with the central bulged portion and adapted to be moved away from or into contact with the beaded edge of the receptacle according to whether the flexible disc is sprung in towards said fingers or away from same, and a plurality of upstanding projections near the periphery of the said disc, the said projections providing in effect a discontinuous flange and being so arranged or disposed that they always tend to protect the bulged portion of the disc and also assist in the closing of the cap.

2. A closure according to claim 1, in which one or more projections are provided near the periphery of the central disc between each of the divisions of the fingers.

3. A closure according to claim 1, in which the projections are of circular formation, substantially as described.

In testimony whereof I have hereunto signed my name.

CHARLES LESLIE NEWLAND.
